L. BARBALICZ.
TOP SPINNING DEVICE.
APPLICATION FILED NOV. 6, 1913.

1,120,886.

Patented Dec. 15, 1914.

UNITED STATES PATENT OFFICE.

LÖRINCZ BARBALICZ, OF CLEVELAND, OHIO.

TOP-SPINNING DEVICE.

1,120,886.

Specification of Letters Patent. Patented Dec. 15, 1914.

Application filed November 6, 1913. Serial No. 799,501.

To all whom it may concern:

Be it known that I, LÖRINCZ BARBALICZ, a subject of the King of Hungary, residing at Cleveland, in the county of Cuyahoga and 5 State of Ohio, have invented certain new and useful Improvements in Top-Spinning Devices, of which the following is a specification.

This invention relates to an improvement 10 in top spinning devices.

The object of the invention is to produce a device of this character that will be simple and neat of construction, and easy of operation.

15 With the above and other objects in view as will appear as the nature of the invention is better understood, the same consists in the novel construction and arrangement of parts of a top spinning device, as will be herein- 20 after fully described and claimed.

In the accompanying drawing forming a part of this specification and in which like characters of reference indicate corresponding parts:—Figure 1 is a perspective view 25 of the device, showing a top separated from the holder. Fig. 2 is a longitudinal sectional view, displaying the position of the top relative to the holder, when in spinning position. Fig. 3 is a top plan view of the holder. 30 Fig. 4 is a longitudinal sectional view through the top.

Referring to the drawings, 1 designates the body of a top, here shown as of gong shape, and provided with a spindle 2 rigidly 35 secured to the body, preferably by being riveted thereto, and having its outer end reduced to provide a peg 3 and at its inner end, adjacent to the body formed with a squared portion 4, the intermediate length of the 40 spindle being cylindrical, as clearly shown in Fig. 1.

The holder comprises a handle 5 provided at one end with a circular head 6 having a central orifice 7. Secured to the head is a 45 top support designated generally 8, the same being a three sided structure made from sheet metal, the top 9 being provided with a

central orifice 10 alining with the orifice in the head, the orifice 10 being provided with a lateral cleft 11, constituting a cord passage, the side 12 being provided with an out-turned flange 13 that is secured to the head 6 by a rivet 14, and the sides 15 being provided with an out-turned flange 16 that is secured to the handle by a rivet 17. 50 55

In the use of the device, the cord C, shown in Fig. 2, is wound about the spindle, being started at the squared portion 4 in order to obtain a firm grip upon the spindle, the winding being continued to a point adjacent 60 to the peg, and then reversed back to the squared portion again. When the winding is completed, the spindle is inserted through the orifice 10, the cord passing through the slot 11, and the peg 3 projecting through the 65 orifice 7, the body resting upon the top of the support. Upon the cord being quickly withdrawn from the spindle, a very rapid rotary motion is imparted to the top, and by giving a slight downward motion, the top 70 is caused to detach itself from the holder and fall to the floor, or to any other suitable support, where it will spin for a considerable time. 75

From the foregoing description, it will be seen that while the improvements herein described are simple in character, that they will be thoroughly effective for the purposes designed, and will co-act in the production of a cheap and highly diverting toy. 80

What I claim as new is:—

A holder for spinning-tops, comprising a handle having a head at one end provided with an orifice, and a skeleton top-support secured to the head, and provided with a 85 laterally slotted orifice alining with the orifice of the head.

In testimony whereof I affix my signature in presence of two witnesses.

LÖRINCZ BARBALICZ.

Witnesses:

G. M. KOVACHY,
ARNOLD CHENCO.
